Application April 18, 1931, Serial No. 531,087
Renewed August 25, 1937

8 Claims. (CL. 78—41)

This invention relates to metal forming presses. One object of the invention is the provision of a press for metal forming or the like, having a reciprocable slide adapted to be connected to and disconnected from a constantly movable member such as a rotatable crank shaft, under the control of the operator, the connection between the crank shaft and the slide member being rendered effective automatically by the press throughout a very substantial portion of the cycle of operations. The press is, therefore, adaptable for operations at very high speeds.

Another object of the invention is the provision of a press having a toggle connection between the crank shaft and a reciprocable slide, provision being made for rendering the toggle connection ineffective or effective, during a cycle of operations.

Another object of the invention is the provision of a high speed metal working press particularly adapted for metal forging, having means operable in timed relation to a crank shaft for gradually operably connecting the crank shaft to a die carrying member so that power may then be positively transmitted from the crank shaft to the die carrying member to move the latter to the work position.

Another object of the invention is the provision of a press having a slide operated from a crank shaft or the like through a plurality of arms or links, mechanism being provided, operated by the movable parts of the press under the control of the operator, for holding the arms or links in power transmitting relationship with respect to one another during the effective part of a stroke of the slide.

A further object is the provision of a press having mechanism of the character mentioned for moving the slide downwardly, upward movement of the slide being caused by fluid pressure means.

Other objects and advantages of the invention will be apparent from the following description, the appended claims and the accompanying drawings, in which—

Fig. 1 is a rear elevation of a portion of a press embodying the present invention, some of the parts being shown in section;

Fig. 2 is a side elevational view of the upper portion of the press;

Fig. 3 is a vertical central section through the upper portion of the press;

Fig. 4 is a detail sectional view on the line 4—4 of Fig. 1; and

Figs. 5, 6, and 7 are diagrammatic views show-

ing the position of the parts while engaging, disengaging and idling respectively.

Referring more particularly to the drawings by reference numerals, like numerals designating similar parts in the several views, 10 designates generally the frame of a press for forming metal or the like. As herein shown the metal forming press is particularly adapted for striking hammer blows in the forging of metal, and is so designed as to be capable of operating at high speed. In 10 the frame is supported a rotatable crank shaft 11 adapted to be driven constantly while the press is in operation, by means of a suitable driving motor and connected gearing, not shown. Slidably mounted in guides 12 provided in opposite 15 sides of the press frame is a slide 13 to which may be affixed a die of suitable shape. The die supported by the slide 13 cooperates with a mating die carried by the bed of the press below the slide.

The slide 13 is urged upwardly at all times in a yielding manner by suitable provision overcoming the weight of the slide, and a down stroke of the slide is obtained by rendering a connection between the slide and the crank shaft effective, 25 the crank shaft then driving the slide downwardly and overcoming the yielding upward force so as to bring the upper die into engagement with the metal supported on the lower die. As herein shown the means for supporting the slide 13 and 30 holding it upwardly in a yielding manner is an air cushion designated generally 15. This air cushion comprises a piston 16 operating in cylinder 17 in which there is air or other suitable fluid under some predetermined pressure. This pressure is supplied to the interior of the cylinder through a pipe 18 in which is a pressure controlling valve that permits the supply of fluid to the cylinder but prevents return into the line. The air supply of the factory can thus be coupled to 40 the pipe 18 and supply air under suitable pressure, which holds the piston 16 up under a force that is greater than the weight of the slide and its associated parts.

The piston 16 is connected by a piston rod 19 to a frame 20 connected by bolts 21 or the like to the upper end 22 of the slide 13. When the piston 16 is pulled down by the slide 13, operated from the crank shaft, the air within the cylinder 17 is compressed, or the pressure originally obtaining within the cylinder is sufficient to overcome the weight of the slide and its associated parts when the driving connection to the crank shaft is rendered ineffective. When the piston 16 returns to its upper position, as shown in Fig. 3, 55

it comes into engagement with a ring 24 which serves as a stop limiting the upward movement of the piston and of the slide. This stop ring is connected by bolts 25 to spacing sleeves 26 which connect through springs 27 to the lower side of the flange 28 on the upper end of the cylinder. The spacing sleeves 26 form a positive stop controlling upward movement of the stop ring 24. It will thus be apparent that the stop ring 24 can move a limited amount under the control of the springs 27 when engaged by the piston to provide a yielding stop at the upper end of movement of the slide 13.

As previously indicated the connection between the slide 13 and the crank shaft is one that, at times, is inoperative, a driving connection being made between the slide and the crank shaft automatically but under the control of the operator. The connection between the slide and crank shaft 20 is in the nature of a toggle embodying a link 30 pivotally connected by pin 31 to the slide and pivotally connected by pin 32 to a crank arm 33 operated by the crank 34 of crank shaft 11. The connecting pin 32 which ties the crank arm 33 25 to link 30 is movable in a forward and rearward direction by mechanism that will be presently described. When moved toward the front of the press a stop surface 36 on arm 30 engages a stop 37 on the rear side wall 38 of the slide. In 30 this position of the parts the connecting pin 32 is a little to the left of a line connecting the axis of pin 31 to the center of the crank shaft, so that the link 30 is held immovable with relation to the slide and is in power transmitting relationship with respect to the arm 33, by reason of 35 the very slight misalignment of the axes of these parts and the upward pressure created on the slide by the air cushion. When the parts are in this position it will be apparent that downward movement of the arm 33 caused by rotation 40 of the crank shaft transmits a downward force in an effective and direct manner to the slide 13.

The connecting pin 32 is connected to a rod 40 pivoted at 41 to the lower end of an arm 42 which 45 is keyed to a shaft 43, rotatably supported in suitable bearing brackets 44 and 45 apparent from Fig. 1. The shaft 43 rotatably supports the hub 46 of a driving arm 47, endwise movement of the hub along the shaft 43 being prevented in 50 any suitable manner as by means of a suitable stop 48. The driving arm 47 projects forwardly, carrying a cam roller 49 at its forward end. This roller operates in a cam groove 50 of a driving cam 51 that is fixed to the end of the crank 55 shaft 11. The driving cam 51 is of single lobe shape so that each revolution of the crank shaft causes a complete oscillation, that is an up and down movement, of the driving arm 47. The hub 46 of the driving arm is adapted to operate the shaft 43 through clutch plates 53 and 54, both 60 of which are keyed to the shaft 43, and both of which are movable in unison toward the right or left, see Fig. 1. Clutch plate 53 is provided with a stop surface 55 engageable with stop surface 65 56 on the driving hub 46. Clutch plate 54 has a stop surface 57 engageable with a stop surface 58 on the clutch hub. When the clutch plates 53 and 54 are simultaneously moved to the right from the position shown in Fig. 1 it will be apparent 70 that the driving hub 46 may operate the clutch plate 53 in one direction, while in the position of the parts shown the driving hub is operating the clutch plate 54 in the other direction.

75 The clutch plates 53 and 54 are provided with

grooves 59 cooperating with rollers 60 carried rigidly by a shift rod 61. This rod is urged toward the left by a spring 62, which therefore tends to couple the clutch plate 54 to the driving hub 46. Rod 61 is moved toward the right 5 to couple the clutch plate 53 to the driving hub by means of a cam 63 operating through roller 64, rod 65, arm 66, shaft 67 and arm 68. The end of the arm 68 engages a groove 69 in the shift rod 61, arms 68 and 66 being rigidly connected to the shaft 67. In the position of the parts corresponding to Fig. 2 the roller 64 is in engagement with a circular portion of the cam, permitting the spring 62 to hold the shift rod over to the left, see Fig. 1, and thus hold clutch 10 plate 54 in engagement with the driving hub 46. This would be the position of the press parts just after starting a cycle of operations. When the cam 63 moves the roller 64 downwardly, however, the shift rod is moved to the right against 20 the pressure of the spring 62, such position of the parts corresponding to the inoperative or ineffective position.

Slidably mounted in a suitable guide 70 is a foot operated member 71 having connection 25 through a suitable linkage 72 to a foot pedal or other similar controlling device adapted to be operated by the operator. Pivotally connected to the upper end of the member 71 is a notched latch 73 engageable with a latch member 74 supported by rod 75. Rod 75 is slidably mounted in the bracket 76, and carries stop 77 at its upper end, the stop 77 and rod 75 being normally held up in a yielding manner by spring 78. In its upper position, with the shift rod 61 in its right-hand position, the stop 77 is in front of a stop plate 80 fixed on the rod 61, holding the clutch plate 53 in engagement with the driving hub. When the latch 73 is pulled downwardly by the operator so as to pull the latch member 74 down, 40 the stop 77 is moved down out of the path of the stop plate 80 so that the latter can be moved to the left by the spring 62. Fixed to the shaft 67 of the mechanism operated by cam 63 is an arm 81, connected through rod 82 and spring 83 45 to the latch 73 so that the latch will be pulled to the right to release the latch member 74 when the spring 62 slides rod 61 to the left and causes 50 counterclockwise rotation of parts 68, 66 and 81. By reason of this construction the operator is 55 permitted to depress the foot pedal or like controlling device so that at the proper time in the cycle of operations the clutch plate 54 will be moved to the position shown in Fig. 1 into engagement with the driving hub. When so moved it releases the latch 73, swinging it to the right, as shown, so that latch member 74 can automatically move into the path of stop plate 80 60 after a sequence of operations has been completed. When the stop plate 80 is held to the right the cam roll 64 is held away from the cam, and the spring 83 is compressed, holding the latch 73 engaged with the latch member 74 if the foot pedal is released, or engaging the latch and latch member when the foot pedal is released. 65

Referring now to Figs. 5, 6 and 7, several positions of the parts are indicated in full lines and in dotted lines, showing the movements of the crank 34, the driving cam 51, arms 47 and 42, crank arm 33, link 30, rod 40, and the slide pin 31. Fig. 7 70 shows the parts while idling, that is when the slide 13 is maintained stationary at the upper end of its stroke while the crank shaft rotates. Under these conditions the slide pin 31 remains stationary while the link 30 and arm 33 move from 75

the full line positions to the dotted line positions, the toggle linkage being always broken so that no force is transmitted to the slide from the crank shaft. The arm 42 is swung outwardly by the 5 rod 40 since the pin 32 is stationary, but this arm 42 is so associated with the shaft 43 (clutch plate 53 engaging driving hub 46) that arm 42 can move counterclockwise with relation to arm 47, the stop surface 55 moving away from the 10 arm 47, the stop surface 56. Therefore, the two arms 42 and 47 are not connected together and up and down movements of the arm 47 as governed by the driving cam 51 are without effect on arm 42.

When the foot pedal is depressed the latch 73 15 pulls down the latch member 74 permitting the spring 62 to move the shift rod 61 and thus bring clutch plate 54 into engagement with the driving hub 46. The arm 47 is then connected to arm 42 insofar as a clockwise rotation is concerned 20 as viewed in Fig. 6, which is a view corresponding to Fig. 1. Starting with the full line position of the parts, a 90° clockwise rotation of the crank shaft causes the pin 32 to move down some distance, during which time the arm 47 is connected 25 to the arm 42 as stop surfaces 58 and 57 are in engagement. The arm 42 is therefore swung clockwise and thus moves the pin 32 to the left at the same time it is being forced downwardly by the crank arm 33. This movement of the pin 32, 30 to the left, has the effect of straightening the toggle, swinging the stop surface 36 against the stop 37 so that the forces may be transmitted from the crank shaft effectively and directly to the slide. The following 90° movement of the crank shaft completing the second half of the downward movement of the slide, of course, moves the pin 32 down still further while the link 30 is fixed on the slide. The arm 42, however, does not move 35 from its dotted line position, as the stop 58 moves 40 away from the stop 57, during this final part of the down stroke of the slide, so that the toggle is maintained substantially straight. In other words link 30 is operatively associated with arm 33 for the effective transmission of forces to the slide 45 during the second half of the down stroke.

The following 90° travel of the crank shaft, during which time the slide starts to rise, moves the parts to the position shown in full lines in Fig. 5. During this 90° of movement the stop 50 surfaces 57 and 58 are approaching each other so that by the time the full line position of Fig. 5 is reached these stop surfaces engage and the toggle parts have just been moved out of alignment. This breaking of the toggle is effected in 55 a positive manner by the stops 57 and 58, if the toggle is not broken by the time the full line position is reached. However, before that time the movement of the upper end of the crank arm 33 to the left has swung the arm 33 out of alignment with the link 30 and upward pressure on the 60 slide created by the air cushion causes the slide to move up rapidly until the stop surfaces 57 and 58 engage. At this time the cam 63 operates the mechanism to swing the clutch plates 53 and 54 65 to the right as viewed in Fig. 1 so that the slide can continue its upward movement under the control of the air cushion, the stop surface 55 moving away from the stop surface 56 as the slide rises to the top of its stroke. These two stop surfaces, however, are brought into engagement when the crank reaches the upper end of its movement as represented in dotted lines in Fig. 5, and at 70 this time the hub 46 is in a position so it can be moved over into engagement with the clutch plate 75 54 again. If the foot pedal is not depressed at

this time the subsequent movements of the hub 46 are without effect on the slide, as the arm 47 is not connected to arm 42 so far as clockwise rotation is concerned, and movements of the crank arm 33 merely have the effect of swinging this arm into an angular relationship with the link 30 as shown in full lines in Fig. 7, previously described. 5

By reason of the construction referred to, it is apparent that at any time desired by the operator, he can place the press in position so that at the proper time in the cycle of operations the press parts will themselves cause the straightening of the toggle arms so that the required pressures can be transmitted from the crank shaft to the slide. This press operated mechanism which 10 straightens the toggle arms into substantial alignment is moved by the press during a very substantial part of the cycle of operations. As herein shown the toggles are being straightened while the crank shaft is moving through a full 90° of 20 travel. No great force need be transmitted to the slide during this first half of the down movement of the slide as the work has not been engaged, and comparatively small and simple parts can, therefore, be employed for bringing the toggle 25 arms into substantial alignment. As the press automatically operates the mechanism that brings the toggle members into alignment during a very substantial angular travel of the crank shaft, the press is particularly adapted for very high speed 30 operation, such as is quite desirable in forging presses and the like. Blows of tremendous force, as much as five hundred tons or more, may be struck by a press operating at a crankshaft speed even greater than 125 R. P. M., in accordance with 35 this invention. Although particularly desirable for hot forging of steel and brass and like material, it is apparent that the press is susceptible to other adaptations and uses.

While the form of apparatus herein described 40 constitutes a preferred embodiment of the invention, it is to be understood that the invention is not limited to this precise form of apparatus, and that changes may be made therein without departing from the scope of the invention which is 45 defined in the appended claims.

What is claimed is:

1. In a press of the character described, a frame, a reciprocable slide guided in said frame, a rotatable operating shaft provided substantially 50 in line with the direction of slide movements and having a driving portion for reciprocating said slide, means for connecting said slide to said driving portion and comprising a toggle connection adapted to be straightened for the transmission of thrust force from shaft to slide and to be collapsed to permit idle movement of said shaft, and means operated by said shaft for rendering said toggle connection operative.

2. In a press of the character described, a 60 frame, a reciprocable slide guided in said frame, an operating shaft provided substantially in line with the direction of slide movement and having a driving portion for reciprocating said slide, means for connecting said slide to said driving 65 portion and comprising a toggle connection adapted to be straightened for the transmission of thrust force from shaft to slide and to be collapsed to permit idle movement of said shaft, fluid pressure means for urging said slide toward 70 said shaft, and means driven in predetermined timed relation with said shaft for rendering said toggle connection operative.

3. In a press of the character described, a 75 frame, a reciprocable slide guided in said frame,

an operating shaft rotatable in said frame and having a driving portion for reciprocating said slide, and means for connecting said slide to said driving portion and comprising a toggle connection adapted to be straightened for the transmission of thrust force as a rigid member from shaft to slide and to be collapsed to permit idle movement of said shaft, means independent of said toggle connection for normally urging said slide toward said shaft, and means for controlling said toggle connection to provide for continued idle rotation of said shaft while the slide remains ineffective.

4. In a press of the character described, a frame, a reciprocable slide guided in said frame, a rotatable operating shaft provided substantially in line with the direction of slide movements and having a driving portion for reciprocating said slide, a crank arm connected to said driving portion, a link pivotally connected to said crank arm and to said slide, said link and crank arm being adapted to be straightened for the transmission of thrust force from shaft to slide and to be collapsed to permit idle movement of said shaft, and means operated by said shaft for straightening said arm and link into alignment during the first half of the downward movement of said driving portion.

5. In a press of the character described, a frame, a reciprocable slide guided in said frame, a rotatable crank shaft provided substantially in line with the direction of slide movements and having a driving portion for reciprocating said slide, a toggle connection connecting said slide to said driving portion and adapted to be straightened for the transmission of thrust force from shaft to slide and to be collapsed to permit idle movement of said shaft, and means for straightening said toggle connection, said last means having provision for gradually accelerating the slide from an upper portion of rest with relation to the movements of said driving portion.

6. In a press of the character described, a frame, a reciprocable die carrying slide guided in said frame, an operating shaft provided substantially in line with the direction of slide movements and having a driving portion for reciprocating said slide, and means for connecting said slide to said driving portion and comprising a toggle connection adapted to be straightened for the transmission of thrust force

from said shaft to slide and to be collapsed to permit idle movement of said shaft, controllable means operated by said shaft in timed relation therewith for straightening said toggle connection at predetermined times in the sequence of movements of said shaft, and manually operable means for controlling said controllable means to render the same effective and ineffective when desired.

7. In a press of the character described, a frame, a reciprocable slide guided thereon, a rotatable shaft mounted in said frame, an arm eccentrically connected to said shaft, a connection between said arm and said slide, a member operable in one direction for operating said connection so the slide is driven by said arm, and operable in the opposite direction so that the arm is ineffective to drive said slide, an oscillatable part driven by said crank shaft, a clutch operable to connect said oscillatable part to said member for movement of said member in one direction, a second clutch operable to connect said oscillatable part to said member for movement of said member in an opposite direction, and means operable in timed relation with said shaft for automatically engaging one clutch and disengaging the other at a predetermined time in a cycle of press operations.

8. An engaging and disengaging device for presses, stamping machines and similar machine tools, comprising in combination an upper tool holder, a work holder to be operated upon by said tool holder, a driving means to actuate said upper tool holder, a crank and toggle connection between said upper tool holder and said driving means, said toggle connection being broken when the driving means is not actuating the upper tool holder and being straightened when the toggle connection is operating the upper tool holder, means to break said toggle connection and to straighten said toggle connection, releasable fluid actuated means for holding the upper tool holder in operative position removed from the work holder when the toggle connection is broken, said crank and toggle connection operating said upper tool holder when the toggle connection is in straightened position against the force exerted by said releasable fluid actuated means.

ARTHUR A. BYERLEIN.
